(57) CLAIM

The ornamental design for hot air popcorn popper machine, as shown and described.

DESCRIPTION

FIG. 1 is a front, side perspective view of our new ornamental design for hot air popcorn popper machine;

FIG. 2 is a front elevation view thereof;

FIG. 3 is a rear elevation view thereof;

FIG. 4 is a left, side elevation view thereof;

FIG. 5 is a right, side elevation view thereof;

FIG. 6 is a top plan view thereof; and,

FIG. 7 is a bottom plan view thereof.

The broken lines shown in the drawings are for illustrative purposes only and form no part of the claimed design.
